UNITED STATES PATENT OFFICE.

HARRY C. NEWMAN, OF LOS ANGELES, CALIFORNIA, ASSIGNOR OF ONE-THIRD TO H. D. EBERLE AND ONE-THIRD TO SPENCER C. ROGERS, BOTH OF LOS ANGELES, CALIFORNIA.

JACK.

Application filed March 28, 1921. Serial No. 456,458.

To all whom it may concern:

Be it known that I, HARRY C. NEWMAN, a citizen of the United States, residing at Los Angeles, in the county of Los Angeles and State of California, have invented a new and useful Improvement in Jacks, of which the following is a specification.

My invention relates to jacks and is particularly applicable to jacks which may be placed under automobiles or trucks to raise same and thus permit replacement and repair of tires. Such jacks must ordinarily be so constructed that they are sufficiently short when in their telescoped position to go under the lowest axle to which it may be desired to apply them, and, at the same time, they must have sufficient length of travel to reach and lift high axles far enough to allow the tires to be removed and replaced.

It is common practice in many forms of jacks to provide means for obtaining an initial adjustment to suit the axle previous to the actual lifting operation. That is, the jack is put under the axle and adjusted to suit the height of the axle.

An object of my invention is to provide a jack which is sufficiently short to go under any automobile or truck axle to which it may need to be applied, and which will automatically and instantly adjust itself to the height of the axle upon starting of operations.

Further objects and advantages will be made evident hereinafter.

Referring to the drawing which is for illustrative purposes only,

Fig. 1 is a side elevation of my invention.

Fig. 2 is a section on a plane represented by the line 2—2 of Fig. 3.

Fig. 3 is a section on a plane represented by the line 3—3 of Fig. 1.

Fig. 4 is a section through the lower portion of the device on a plane represented by the line 4—4 of Fig. 3.

In the form of the invention illustrated, a base 11 is provided in which is secured in fluid tight relationship an outer tube 12 and an inner tube 13, the tops of these tubes being connected together by a cap 14. The space between the tubes 12 and 13 forms an oil reservoir. Sliding in liquid tight contact

with the inner wall of the tube 13 is a lift bar or plunger 20, this plunger passing through a stuffing box 21 in the cap 14. Sliding in a cavity in the center of the lift bar 20 is a ratchet bar 22. The ratchet bar 22 has a central cavity 23 in which a compression spring 24 is placed, the top of the cavity being closed by a threaded end 25 on a saddle 26. The spring 24 tends to force the ratchet bar 22 upwardly out of the cavity in the lift bar 20. Pivoted on a pin 27 carried by the lift bar 20 is a pawl 28 of proper shape to engage ratchet teeth 29 formed in the ratchet bar 22. A cup leather may be used to assist in making a liquid tight joint between the plunger or lift bar 20 and the walls of the tube 13. A passage 30 which may be closed by a screw valve 31 connects the working space 32 below the lift bar 20 inside the tube 13 with the oil reservoir 15.

Secured in the base 11 is a pump cylinder 35 in which a plunger 36 is free to slide, the plunger 36 being connected to a piston rod 37 which is pivoted on a pin 38 in a lever 39. The lever 39 is fulcrumed on a pin 40 carried by a link 41 pivoted on a pin 42 carried in the base 11. A detachable handle 43 is provided for the lever 39. The space 45 inside the tube 35 below the plunger 36 communicates with a passage 46 which is connected through a valve 47 with the space 15 and through a valve 48 with the space 32. The valve 47 is provided with a spring holding it normally closed, the valve 48 working by gravity. The valve 47 is so constructed that oil may flow from the space 15 into the passage 46 but not in the opposite direction and the valve 48 is so constructed that oil may flow from the passage 46 into the space 32 but not in the opposite direction. The pawl 28 is provided with a tail 50 and with a spring 51.

The method of operation is as follows:

The valve 31 being opened, it is possible to push the ratchet bar 22 and lift bar 20 to their extreme lower position as shown in full lines in Fig. 2. The ratchet bar and the lift bar move down together and the tail 50 of the pawl 28 forces the pawl into engagement with the sloping top of the teeth 29, thus holding the ratchet bar 22 in its lower

position against the upward thrust of the spring 24.

With the parts in this position, i. e. in the position shown in full lines in Fig. 2, the 5 jack has a minimum height and may be slipped under very low axles. Whenever it is desired to raise an axle or other load, the valve 31 is closed and the plunger 36 is reciprocated by moving the handle 43 up and down. At each upward stroke of the handle, 10 oil is drawn through the valve 47 from the reservoir 15 into the space 45. On the down stroke, this same oil is forced from the space 45 through the valve 48 into the space 32, thus forcing the lift bar 20 upwardly and at 15 the same time raising the saddle 26 and the ratchet bar 22. As soon, however, as the lift bar 20 has moved upwardly a short distance, the tail 50 of the pawl 28 leaves the cap 14 20 and the pawl 28 is forced in a clockwise direction around the pin 27 due to the upward thrust of the spring 24. This releases the pawl 28 from the top of the teeth 29 and the spring 24 acts freely, forcing the saddle 26 upwardly until it either is extended to its 25 full length or until it meets obstruction.

In practice, the jack is telescoped to its full degree as shown in full lines in Fig. 2, and is placed on the ground and moved to 30 a position directly below the axle. A few strokes of the handle 43 forces the plunger 20 far enough up to release the pawl 28 and the saddle 26 shoots upwardly under the action of the spring 24 until it seats under- 35 neath the axle. If now the handle 43 is operated further, the lift bar 20 rises and the pawl 28 is forced into engagement with the under side of one of the teeth 29 by the spring 51. A further operation of the han- 40 dle 43 causes the lift bar 20 to raise the ratchet bar 22 by means of the pawl 28.

It will, therefore, be seen that in practice 45 the jack may be carried in its collapsed position as shown in Fig. 2, the spring 24 being restrained by the tail 50 of the pawl 28 resting on the top of the cap 14. It will be fur- 50 ther seen that as soon as the jack is used, it automatically adjusts itself to the height of the load which it is desired to lift without the necessity of the operator taking any pains with its adjustment. This is a very 55 important feature as jacks must ordinarily be placed under an automobile a consider- able distance and their manipulation in this cramped position is difficult. As the auto- 60 mobile is ordinarily more or less covered with dirt and grease, the easier it is to adjust the jack the less dirty and unpleasant the operation becomes. Whenever it is desired 65 to lower the jack, the valve 31 is opened, allowing free communication between the space 32 and the space 15. With the valve 31 open, it is possible to push the saddle 26 downwardly until the parts assume the posi- 70 tion indicated in full lines in Fig. 2. A

check valve 100 is provided in the cap 14 which is so arranged to prevent the escape of oil therefrom.

I claim as my invention:

1. In a jack, the combination of a lift- 70 bar; means for forcing said lift bar up- wardly; a ratchet bar sliding vertically in said lift bar; elastic means for forcing said ratchet bar upwardly in said lift bar; and locking means for preventing said ratchet 75 bar from being forced downwardly in said lift bar.

2. In a jack, the combination of a lift bar; means for forcing said lift bar up- 80 wardly; a ratchet bar sliding vertically in said lift bar; elastic means for forcing said ratchet bar upwardly in said lift bar; and a pawl pivoted to said lift bar and engaging teeth formed on said ratchet bar in such a manner as to prevent said ratchet bar from 85 being forced downwardly in said lift bar, when said pawl is engaged.

3. In a jack, the combination of a lift bar; means for forcing said lift bar upwardly; a 90 ratchet bar sliding vertically in said lift bar; a compression spring between said lift bar and said ratchet bar so disposed as to force said ratchet bar upwardly in said lift bar; and locking means for preventing said ratchet bar from being forced downwardly 95 in said lift bar.

4. In a jack, the combination of a lift bar; means for forcing said lift bar up- 100 wardly; a ratchet bar sliding vertically in said lift bar; a compression spring between said lift bar and said ratchet bar so disposed as to force said ratchet bar upwardly in said lift bar; and a pawl pivoted to said lift bar and engaging teeth formed on said ratchet bar in such a manner as to prevent 105 said ratchet bar from being forced downwardly in said lift bar, when said pawl is engaged.

5. In a jack, the combination of a sup- 110 porting structure; a lift bar sliding vertically in said structure; means for forcing said lift bar to move upwards in said structure; a ratchet bar sliding vertically; spring means for forcing said ratchet bar to move up- 115 wards; and ratchet means whereby said lift bar raises said ratchet bar.

6. In a jack, the combination of a ratchet bar; elastic means for forcing that bar up- 120 wards until it strikes the load to be lifted; and power multiplying means thereafter causing said bar to lift said load.

7. In a jack, the combination of a ratchet bar; elastic means for forcing that bar up- 125 wards until it strikes the load to be lifted; ratchet teeth formed on said ratchet bar; and power multiplying means acting on said teeth to raise said ratchet bar and said load.

8. In a jack, the combination of a ratchet bar; elastic means for forcing that bar up-

wards until it strikes the load to be lifted; ratchet teeth formed on said ratchet bar; a pawl engaging said teeth to lift said ratchet bar and said load; and power multiplying means for forcing said pawl upwards. 5

9. In a jack, the combination of a ratchet bar; elastic means for forcing that bar upwards until it strikes the load to be lifted; ratchet teeth formed on said ratchet bar; a 10 pawl engaging said teeth to lift said ratchet bar and said load; a lift bar on which said pawl is pivoted; and power multiplying means for forcing said lift bar upwards.

10. In a jack, the combination of a ratchet bar; elastic means for forcing that bar upwards until it strikes the load to be lifted; 15

means for initially preventing said upward movement of said bar; and power multiplying means thereafter causing said bar to lift said load. 20

11. In a jack, the combination of a ratchet bar; elastic means for forcing that bar upwards until it strikes the load to be lifted; means for initially preventing said upward movement of said bar; ratchet teeth formed 25 on said ratchet bar; and power multiplying means acting on said teeth to raise said ratchet bar and said load.

In testimony whereof, I have hereunto set my hand at Los Angeles, California, this 30 22nd day of March, 1921.

HARRY C. NEWMAN.
